(57) **CLAIM**

The ornamental design for a board assembly, as shown and described.

DESCRIPTION

FIG. 1 is a front and right side perspective view of a board assembly showing my new design;

FIG. 2 is a back and left side perspective view thereof; and, FIG. 3 is an enlarged front perspective view of the end portions for clarity of the disclosure.

The broken lines in the drawings illustrate portions of the board assembly and form no part of the claimed design.
